UNITED STATES PATENT OFFICE.

GUSTAV N. MEVES, OF DAVENPORT, IOWA.

OPERATING MECHANISM FOR WASHING-MACHINES.

961,879.

Specification of Letters Patent. Patented June 21, 1910.

Application filed November 4, 1909. Serial No. 526,212.

To all whom it may concern:

Be it known that I, GUSTAV N. MEVES, a citizen of the United States, and a resident of Davenport, in the county of Scott and State of Iowa, have invented certain new and useful Improvements in Operating Mechanism for Washing-Machines; and I do hereby declare that the following is a full, clear, and exact description thereof, reference being had to the accompanying drawings, and to the characters of reference marked thereon, which form a part of this specification.

This invention relates to improvements in operating mechanisms for washing and like machines of that class having a stirrer head shaft which is given a rotary reciprocatory motion, and the invention consists in the matters hereinafter set forth and more particularly pointed out in the appended claims.

The invention relates more specifically to that class of such machines wherein a balance wheel or other power storing device is connected to the actuating means for the stirrer or dasher shaft in such a way as to substantially reduce the power required to operate the machine after the mechanism is set in motion, and to relieve the reversible parts from shocks and jars at their points of reversal.

My improved operating mechanism herein shown embodies a hand-actuated rocking element for giving motion to the rotary reciprocatory shaft, but it will be understood that other forms of actuating elements may be employed, and also that the mechanism, as a whole, may be used in other machines than washing machines.

In the drawings, Figure 1 is a vertical sectional view of a washing machine equipped with an operating device embodying my invention. Fig. 2 is a side elevation of the actuating means for the dasher shaft. Fig. 3 is a top plan view of the machine. Fig. 4 is a horizontal sectional view on the line 4-4 of Fig. 1. Fig. 5 is a detail rear elevation of the tail piece of the lid and the gearing supported thereby.

The tub 10, the stirrer head 11 and stirrer head shaft 12 are of the usual construction in this type of machine. Said shaft has bearing in a sleeve 13 located in a central opening in the swinging portion 14 of the

lid or cover, and is made integral with a 55 plate 15 that is fixed on the upper side of the said swinging portion of the lid or cover. The said swinging portion of the lid or cover is hinged at 16 to a metal tail piece, or the non-rising portion 17 of the top wall 60 of the tub. A beveled pinion 18 at the upper end of the stirrer head shaft meshes with the gear sector 19 of a rocking member 20, which latter is pivoted to an upright standard or bracket 21 that rises from or is 65 made integral with the frame plate 15; said standard being provided with a horizontal pivot pin or stud 22 which engages a bearing aperture in the rocking member. The rocking member has a socket piece 23 in 70 which fits the lower end of an operating handle 24 by which the rocking member is swung on its axis to impart rotary reciprocatory motion to the stirrer head shaft.

Located beneath the bottom 25 of the tub 75 is a balance wheel 26 arranged to rotate in a vertical plane. Said balance wheel is shown as fixed to a horizontal, rotative shaft 27 that is rotatively mounted in the parallel members 28, 28 of an underframe arranged 80 beneath the tub bottom. Said under-frame consists, as herein shown, in addition to the parallel members 28, of other members 29, the four frame members being arranged in the form of an open rectangle and attached 85 together at their ends and to the legs 30 of the tub by means of angle pieces 31, 31 and bolts 32, 32, as shown in Fig. 4. The shaft 27 is mounted in brackets 34, 34 carried by the under-frame members 28, said brackets 90 preferably embodying anti-friction media to reduce the friction at these points.

The balance wheel shaft is provided at one end, outside of its adjacent bearing bracket 34, with a beveled pinion 36 that is fixed 95 non-rotatively to the shaft. The said beveled pinion meshes with a horizontally arranged gear wheel 37 that is fixed to the lower end of a vertical, rotative shaft 38 arranged at the side of the tub and extending at 100 its upper end to the top of the tub. The lower end of said shaft has bearing in a bracket arm 39, herein shown as formed an integral part of the adjacent bracket 34 of the balance wheel shaft. The upper end of said 105 shaft 38 is rotatively mounted in a suitable bearing bracket 41, shown as made integral with the tail piece 17 of the lid, as will here-

inafter more fully appear. The shaft 38 carries at its upper end above the bearing bracket 41, a beveled pinion 42 that is non-rotatively fixed thereto. Between the lower 5 end of the hub of the beveled pinion 42 and the bearing bracket 41 are interposed anti-friction balls 43 which serve to carry the weight of the shaft and parts supported thereby, and to reduce the friction between 10 the shaft and its bearing support. The said beveled pinion 42 meshes with a gear wheel 45 that is arranged in a vertical plane, and is mounted on a pin or stud 46 carried by a lug 47 which, as herein shown, is made integral 15 with the tail piece 17. The said tail piece is formed with a curved notch or recess 48 that opens on the top and rear side of the tail piece to receive a portion of the gear wheel 45, the bottom of said recess being curved to correspond with the circumference 20 of the gear wheel 45. The bearing bracket 41 for the shaft 38 extends rearwardly and laterally from the rear end of the curved bottom of said recess 48 of the 25 tail piece and, desirably a housing 51, made integral with said bracket, is arranged to inclose the beveled pinion. Furthermore a casing or housing 52 may be arranged to partially inclose the large gear wheel 45 and 30 may be made integral with the cast metal tail piece. The pinion housing is made of such dimensions as to permit the pinion to be inserted to place in the integral housing. The said gear wheel 45 is connected with the 35 rocking actuating device for the stirrer shaft by means imparting thereto and to the shaft 38 continuous rotary motion in one direction and such unidirectional motion is transmitted to the balance wheel to rotate the latter 40 at high speed. The connections between said gear wheel 45 and the rocking actuating device 20, as herein shown, is made as follows: 45 designates a pitman that is pivotally connected at its outer end with a stud or pin 56 fixed to and disposed eccentrically on the gear wheel 45. The inner end of said link is pivotally connected, as by means of the pin 57, with the lower arm 58 of a vertically swinging lever 59, said arm 58 being laterally directed, as shown at 59^a, for connection 50 with the inner end of the pitman. The said lever 59 is pivoted near its upper end on a horizontal pivot pin or stud 60 that extends inwardly from the upper end of a standard 55 61 which rises from the frame plate 15 and is located laterally at one side of the rocking actuating member 20. The upper, shorter arm 62 of said lever is loosely or pivotally connected to a pivot pin or stud 63 60 that extends laterally from the rocking gear sector 20. As herein shown the shorter arm 65 of said lever is formed with an upwardly opening notch 64 which is arranged to fit over a bearing roller 65 that is mounted on 65 said pin or stud 62. The said pitman is

curved upwardly just inside of its outer end, as shown in Fig. 1, so as to clear the inner notched side of the tail piece, and said notch is made wide enough to receive the pitman and the stud 56.

In order that the swinging portion of the top wall or lid may be swung backwardly to open the tub, the link is detachably and pivotally connected with the lower end of the lever. To this end the inner end of the 70 pitman is provided with a downwardly opening hook portion 67 which engages over said pivot stud 57. Any suitable locking device may be employed to lock the pitman detachably to said pin or stud.

In the operation of the mechanism described the hand lever is grasped by the operator and swung from side to side and operates, through the rocking gear sector member and the meshing pinion, to impart rotary reciprocatory motion to the dasher shaft. The rocking motion of said actuating member is transmitted through the vertically swinging lever 59 and pitman 55 to the gear wheel 45, at which point the motion is translated into a continuous rotation of said gear wheel and of the vertical shaft connected therewith and thence to the balance wheel below the tub. The ratios of the gear wheel and pinion at the upper end of 90 the shaft and the gear wheel and pinion at the lower end of the shaft are such as to increase the speed of the balance wheel to a suitably high point, and the momentum of the balance wheel serves to assist the operation of the actuating device for the stirrer shaft backwardly through the gearing described and also to relieve the reversible parts of shocks and jars at their points of reversal.

The arrangement of the tail piece provided with the recess to receive a portion of the gear wheel at the upper end of the rotative, vertical shaft, enables the center of said wheel and the shaft to be placed at a 11 minimum distance from the tub and contributes to the compactness of the machine. Moreover the tail piece, constituting part of the top wall of the tub, as it does, and formed to provide the fixed bearings for the 11 gears at the upper end of the vertical, rotative shaft, serves to simplify and strengthen the construction.

The arrangement of the lever 59 between the rocking gear sector and the pitman 55 12 constitutes a compound system of levers which serves to increase the driving efficiency of the power stored in the balance wheel and thereby decrease the manual power required to operate the mechanism 12 after it is started in operation.

While I have described the illustrated embodiment of my invention with considerable particularity, it will be understood that the structural details thereof may be varied 12

within the spirit and scope of the invention, and I do not wish to limit the invention to such details except as hereinafter made the subject of specific claims.

5 I claim as my invention:

1. Operating mechanism for washing and like machines comprising, in combination, a vertical shaft capable of rotary reciprocatory motion, actuating means for imparting 10 rotary reciprocatory motion to said shaft, a balance wheel arranged below said shaft to rotate in a vertical plane, and speed increasing gear mechanism operatively connecting said actuating means and balance wheel, embracing a vertical shaft which is rotated continuously in one direction by said actuating means and arranged to impart a continuous high speed rotation to the balance wheel.
- 20 2. Operating mechanism for washing and like machines comprising, in combination, a vertical shaft capable of rotary reciprocatory motion, actuating means for imparting rotary reciprocatory motion to said shaft, a vertically arranged balance wheel below said shaft, a horizontal rotative shaft to which said balance wheel is fixed and speed increasing gear mechanism operatively connecting said actuating means and said balance wheel shaft, embracing a vertical rotative shaft operatively connected at its upper end with said actuating means, a beveled gear wheel on the lower end of the shaft and a beveled pinion on the balance wheel shaft meshing with said gear wheel.

30 3. Operating mechanism for washing machines comprising, in combination, a vertical shaft capable of rotary reciprocatory motion, actuating means for imparting rotary reciprocatory motion to said shaft, a vertically disposed balance wheel below the shaft, a horizontal, rotative shaft to which said balance wheel is fixed, a vertical, rotative shaft, a gear wheel on the lower end of said latter shaft, a pinion on the balance wheel shaft meshing with said gear wheel, a pinion on the upper end of said vertical, rotative shaft, a gear wheel meshing with said latter pinion and a pitman connected 40 with said latter gear wheel and operatively connected with said actuating means:

4. Mechanism for operating washing machines comprising, in combination, a shaft capable of rotary reciprocatory motion, actuating means for imparting rotary reciprocatory motion to said shaft, a balance wheel and speed increasing gear mechanism connecting said balance wheel and actuating means embracing a rotative shaft operatively connected at one end with the balance wheel and a lever arranged between and connected to the other end of said rotative shaft and said actuating means.

5. Operating mechanism for washing machines comprising, in combination, a verti-

cal shaft capable of rotary reciprocatory motion, rocking actuating means for imparting rotary reciprocatory motion to said shaft, a balance wheel arranged below said shaft, a vertical, rotative shaft operatively connected at its lower end with the balance wheel and operative connections between the upper end of said shaft and said operating means embracing a pitman operatively connected at one end with said upper end of the shaft, and a swinging lever to which the other end of said pitman is pivoted, said lever being connected to said rocking actuating means.

6. Operating mechanism for washing and like machines comprising, in combination, a shaft capable of rotary reciprocatory motion, a pinion on said shaft, a rocking gear sector meshing with said pinion, a balance wheel, a rotative shaft operatively connected at one end to said balance wheel, a pinion fixed to the other end of said rotative shaft, a gear wheel meshing with said pinion and provided with an eccentrically arranged stud, a pitman connected at one end to the said stud, and a swinging lever connected to said rocking gear sector and to said pitman.

7. Operating mechanism for washing and like machines comprising, in combination, a shaft capable of rotary reciprocatory motion, a pinion fixed to said shaft, a rocking gear sector meshing with the pinion, a balance wheel arranged below said shaft, a horizontal, rotative shaft to which said balance wheel is fixed, a pinion on the latter shaft, a vertical, rotative shaft, a gear wheel fixed to the lower end of said vertical shaft and meshing with said latter pinion, a pinion on the upper end of said vertical shaft, a gear wheel meshing with said latter pinion, a pitman connected with the last mentioned gear wheel and a swinging lever which is connected to the rocking sector and to the said pitman.

8. Operating mechanism for washing and like machines comprising, in combination, a vertical shaft capable of rotary reciprocatory motion, actuating means for imparting rotary reciprocatory motion to said shaft, a balance wheel arranged below said shaft to rotate in a vertical plane and an upright shaft operatively connected at its upper and lower ends to said balance wheel and actuating device, respectively, and arranged to transmit a unidirectional high speed rotation to the balance wheel.

9. Operating mechanism for washing and like machines comprising, in combination, a vertical shaft capable of rotary reciprocatory motion, actuating means for imparting rotary reciprocatory motion to said shaft, a balance wheel arranged below said shaft to rotate in a vertical plane, a horizontal rotative shaft on which said balance wheel is mounted and speed increasing gear

mechanism for the balance wheel operatively connecting said actuating means and said horizontal shaft and arranged to impart a unidirectional high speed rotation to the 5 balance wheel.

10. Operating mechanism for washing machines and the like comprising in combination with a body, an operating shaft capable of rotary reciprocatory motion, a reversing gear mechanism for imparting rotary reciprocatory motion to said shaft, a horizontal, rotary shaft below said body, a balance wheel mounted on said shaft and

an upright, rotative shaft operatively connected at its upper end with said reversing gear mechanism and operatively connected at its lower end with said balance wheel shaft.

In testimony, that I claim the foregoing as my invention I affix my signature in the presence of two witnesses, this 23rd day of October A. D. 1909.

GUSTAV N. MEVES.
